DESIGN FOR A PLAY HORSE

John Burns, Kenosha, Wis.

Application February 4, 1937, Serial No. 67,445

Term of patent 7 years

To all whom it may concern:

Be it known that I, John Burns, a citizen of the United States, residing at Kenosha, in the county of Kenosha and State of Wisconsin, have invented a new, original, and ornamental Design for a Play Horse, of which the following is a specification, reference being had to the accompanying drawings, forming a part thereof.

Fig. 1 is a view in side elevation of a play horse showing my new design;

Fig. 2 is a view in front elevation of the play horse shown in Fig. 1, the bridle and rein being omitted; and

Fig. 3 is a plan view of the play horse.

I claim:

The ornamental design for a play horse, as shown.

JOHN BURNS.
